UNITED STATES PATENT OFFICE

135,984

DESIGN FOR A COMBINED MANICURE IMPLEMENT AND NAIL FILE

Semmy S. Wechsler, New York, N. Y.

Application May 26, 1943, Serial No. 110,304

Term of patent 3½ years

To all whom it may concern:

Be it known that I, Semmy S. Wechsler, stateless, being formerly a citizen of Germany and having filed my first citizenship papers in the United States, a resident of New York, in the county of New York and State of New York, have invented a new, original, and ornamental Design for a Combined Manicure Implement and Nail File, of which the following is a specification, reference being had to the accompanying drawing, forming a part thereof, and of which Figure 1 is a front view of a combined manicure implement and nail file showing my new design; Fig. 2 is an edge view thereof; and Fig. 3 is a rear view thereof.

I claim:

The ornamental design for a combined manicure implement and nail file, substantially as shown.

SEMMY S. WECHSLER.
